[75] Inventor: Maurice Cohen, Miami, Fla.

Primary Examiner—Bruce W. Dunkins
Attorney, Agent, or Firm—Salter & Michaelson

[73] Assignee: Capitol Hardware Mfg. Co., Inc., Chicago, Ill.

[57] CLAIM

[] Term: 14 Years

The ornamental design for a base for a garment display rack, substantially as shown and described.

[21] Appl. No.: 792,693

DESCRIPTION

[22] Filed: Oct. 28, 1985

FIG. 1 is a perspective view of a base for a garment display rack showing my new design;

[52] U.S. Cl. D6/498; D6/411;
D6/415

FIG. 2 is a top plan view thereof;
FIG. 3 is a side elevational view wherein portions thereof have been broken away for convenience of illustration.

[58] Field of Search D6/360, 411, 462, 498,
D6/495, 415

FIG. 4 is a bottom plan view thereof.
The broken lines illustrated in FIG. 1 are for illustrative purposes only.
